UNITED STATES PATENT OFFICE

JOSEPH POELTL, OF ST. PAUL, MINNESOTA

PLAYING DEVICE FOR PIANOS AND THE LIKE

Application filed April 30, 1929. Serial No. 359,361.

My invention relates to a device for facilitating the playing of a musical instrument having a standard type of keyboard such as a piano or organ. The main object is to provide a simple, efficient and portable device which may be readily attached to a piano and is easily operated to play selective chords and accompanying harmonious notes, such playing being easily accomplished by unskilled players and even by persons who have had no musical training. The device provides further any combination of chording effects as proper accompaniment for orchestral music in which for example the piano is played to accompany violin, mandolin, bass violin, cornet or any combination of wind and string instruments.

It is well known that in orchestral arrangements of music the piano music is mainly or entirely so-called "chording", generally sufficient and always pleasing to the ear. My device is designed to provide said chord playing with positive harmonious combinations, eliminating the direct touch of the fingers on the keys. Music written in the usual way is also eliminated, it being merely necessary to have properly spaced chord designations printed at or near the bars on which the melody is printed. Further objects and advantages of my improved playing device are hereinafter fully disclosed and illustrated in the accompanying drawing, in which,—

Fig. 1 is a top view of the key-board of a piano and my device attached thereto in operative position; the key engaging members of my device on approximately the right half of the device being omitted.

Fig. 2 is a front view of my device alone and showing only one half of the vertically reciprocable bar members.

Fig. 3 is a vertical sectional view of my device about as on line 3—3 of Fig. 2 or line 3 of Fig. 1 showing mainly one key depressing member.

Fig. 4 is an enlarged detail view of the upper part of Fig. 3 and a modification of the playing means.

Figs. 5 and 6 are a pair of harmonized key depressing plates of which Fig. 5 shows the bass clef note sounding means actually in

operative position, while Fig. 6 is a like plate for higher chord-notes corresponding to the bass notes and to be played with and in harmony with the latter.

Fig. 7 is a top view of the toe portion of a shoe and an attachment therefor designed to facilitate playing of a piano with my device.

Referring to the drawing by reference numerals, 10 designates the key-board frame of a piano, organ or like instrument, and below said frame the usual front board 11 of the instrument but set back from the front line of the keys designated collectively as K, but designated in rotation by their correct key designation in Fig. 5.

My device comprises a quadrangular main frame in upright plane, the vertical side members designated 12, the top horizontal member 13, the bottom member 14, an upper horizontal rod-guiding member 15 and below the latter a like member 16, all preferably of light angle iron material and suitably braced as may be necessary.

17 are attachment bolts slidably engaged in frame parts 12 and having each a suitable hook 17H at one end for engaging a shoulder 10S of the key board frame and the parts of said bolts engaging in the frame being threaded for a thumb screw or nut 18 (see Fig. 3) to be adjusted to clamp the main frame to the front edge of the instrument member 10 rigidly. The main frame horizontal bar 15 is preferably about on a level with upper edge of instrument member 10 when the device is in operative position and thus the upper bar 13 is in a plane above the keys of the instrument. The lower part of the frame may be held in necessary elevated position from the floor by two vertically adjustable foot pieces 30 (see Figs. 2 and 3). I have now described the preferred type of main frame and details comprising the stationary parts of the device.

The key engaging and playing parts of my device will now be described. They comprise a series of horizontally spaced, vertically reciprocable player-rods 19, all slidably mounted in the horizontal webs of the frame members 14, 15 and 16.

All these player-rods 19 are of elongated, inverted L-shape, the upper horizontal arm 19A of each extending forward horizontally toward the key-board of the instrument and above it, said arm being guided in a vertical slit 13S of frame member 13 (see Figs. 2 and 3), said arm extending forward thereof and thence down in a vertical extremity 19B, directed toward the keys of the instrument (see Figs. 3 and 4). The lower end of arm 19B is fixed to a key-engaging plate 20 which is held in vertical plane and extends transversely over a number of the keys K.

All the said plates are arranged over the keys in any suitable staggered arrangement as best shown in Fig. 1 and as all the player-rod members attached to the plates 20 are spaced apart horizontally and arms 19A thereof of various corresponding lengths it is obvious that any number of the player rods can be manipulated vertically to engage the keys without interfering with the adjacent player rods and plates. On each rod 19 above frame member 15 is a collar 21 and between said collar and the member 15, about each rod, is a compression coil spring 22 normally pressing its rod upwardly and into stop position against the top of its guide slit 13S in frame member 13.

20F are a number of downwardly directed fingers formed integral with each plate 20, the number and spacing of these fingers being predetermined to engage certain of the keys K whether major or minor notes but in all cases to sound a harmonious chord when rod 19 is pressed down as with a hand 27 in Fig. 2 bearing down on said rod on its part 19A outwardly of bar 13, as clearly shown. The playing means described may be divided into right and left groups of which the left group, shown in full in Fig. 1, are used to sound bass-clef notes and the right hand group to sound groups of notes in higher corresponding keys and groups. For example, in playing the initial chords of a piece of waltz music in the key of C the bass-clef keys C—C, one octave apart, are first sounded (see Fig. 5) by depressing a rod as marked 19C in Fig. 1. Then the bar as 19C' of Fig. 50 1 is depressed two times to sound a higher toned chord in the same key, the bar 20 of the latter being formed to press, for example, the keys C, E, G and C, harmonizing in sound with the bass clef notes first sounded. Obviously any combination of chords may thus be played by manipulating the properly harmonized key-plates in harmony and to accompany other instruments.

In Fig. 4 I have shown a modified playing device; namely, a finger-engaging lever 23 for each rod 19, said lever normally in horizontal plane and pivoted as at 24 in the front part of frame member 13 extending rearwardly from said pivot and having a downwardly directed arm, bifurcated to straddle and rest on the

upper and outer part of rod section 19A, and on the free end of said lever may be provided a button 25. The chords are played by simply depressing the buttons 25 which in turn press 19A down and the respective plates 20 to engage the keys K.

Another feature of my device is a foot pedal member 26 provided at the lower end of each rod 19 and projecting outwardly and horizontally toward the player seated before the device. In Figs. 1 and 2 the lower horizontal frame bar 14 is a Z-bar with its web in horizontal plane and drilled for slidably retaining the lower ends of all the rods 19. The lower ends of the rods extend below this web where the pedals 26 are attached to them, said pedals being guided in the vertical slits 14S in the adjacent outer and vertical flange of the frame member 14 (see Figs. 2 and 3). All the pedals will of course be in a horizontal row and may be manipulated to play chords as desired by downward pressure thereon by the operator's foot 28 (Fig. 7). To facilitate playing by foot I provide a metal shoe engaging clip 29 with side flanges 29F arranged to be slipped on and frictionally engage the sole of a shoe and having an integral forwardly directed finger extending forward centrally from the toe of the shoe, as shown, to be pressed down on the pedals 26. The player so equipped need not of course use the hand manipulating means described.

The operation of my device has been fully disclosed in the above specification. It is obvious and considered as being within the scope of this invention to make a number of modifications in details of construction. For example, other means for fastening the device to a piano may be used as necessary, the foot-pedals 26 and the finger operated levers 23—25 may be marked with numbers or letters indicating the harmonized pairs of chord playing means and the staggered arrangement of the plates 20 may be other than that shown to insure clearance of moving parts.

I claim:

1. A player device for instruments having a row of depressible keys to produce musical sounds, said device comprising a quadrangular normally upright frame and means thereon for attaching the frame in proximity to the keys of the instrument, a row of upright, horizontally spaced and vertically reciprocable rods mounted in said frame, yieldable means normally pressing each said rod upwardly to a predetermined height, each said rod extended over the keys horizontally, thence downwardly toward the keys, a key engaging plate fixed on the latter end of the rod and normally in position over the keys, projections on the lower part of each said plate to engage certain predetermined keys when the rod is pressed downwardly, said yieldable means adapted to raise said key en- 115

- 125
- 130

gaging plate after each said downward movement, and dual manually engageable means for each said rod to press it down and produce sound selectively by hand or foot contact.

5 2. The structure specified in claim 1 in which said frame includes an upper horizontal guide bar normally in position parallel to the row of keys and above them, said guide bar having a vertical flange with a row of slits each to guide vertically one of said reciprocable rods; a lower horizontal bar in said frame with apertures each for guiding a lower end portion of one of said rods, a pedal member 10 fixed on each rod below its aperture and means provided in said lower bar comprising a vertical slit provided in a flange of said bar engaged by said pedal.

15 3. The structure specified in claim 1 and hand operated rod reciprocating means comprising for each rod a lever pivotally mounted on the top frame member extending from its pivot away from the key board and over the rod, a finger extending down from said 20 lever and adapted to engage the reciprocable rod below it, and finger engaging means at the free end of said lever to be depressed, for the purpose described.

25 4. A playing device for instruments having a key board, comprising a portable frame adapted to be removably attached to said key board part of the instrument, a number of vertically reciprocable rods mounted in said frame, spring means yieldingly impelling said rods upwardly, a key engaging plate 30 fixed on each said rod and formed with irregular lower edge normally held close to the keys and adapted to engage certain of said keys to produce predetermined musical chords or combinations of notes.

35 In testimony whereof I affix my signature.
JOSEPH POELTL.
